BIT AND TOOL HOLDER

Ole Severson, Shelton, Conn., assignor to The
Apex Tool & Cutter Company, Inc., a corpora-
tion of Connecticut

Application September 9, 1933, Serial No. 688,731

1 Claim. (Cl. 29—100)

This invention relates to improvements in bits and tool holders, and is particularly concerned with holders for the tools of metal working machines, such, for instance, as for the holding of tools for turning, boring and planing machines.

It is among the general objects of the invention to provide a simple, economical and efficient tool holder of the class designated.

It is among the more specific objects to provide a tool holder having a minimum number of parts, and which lends itself to ease of adjustment and to particular rigidity in the proper securement therein of a metal working tool or bit. Numerous other objects will be apparent from a consideration of the drawing and the following specification.

In the drawing, Figure 1 is a plan view of one preferred embodiment of the invention with the tool bit in place.

Figure 2 is a side elevation of the device shown in Figure 1, the same being broken away on the section line 2—2 of Figure 1.

Figure 3 is an end elevation of that form of the invention shown in Figures 1 and 2; and

Figures 4 and 5 are views illustrating possible modifications of tool bits which may be used in connection with the holder.

In tool holders of the class to which this invention relates, the development of simplicity and the reduction of the number of parts, without the loss of security in the rigid clamping of the bit therein, is one of the main problems encountered. Up to the present time, it has been the general practice to use for such securement a simple securing element such as a screw, which, normally, presses directly against the bit so as to secure it against an oppositely disposed face.

Attempts have been made to use intermediate cam faced elements, so that the securing screw may act indirectly therethrough as a means of urging the bit in a direction at an angle to the thrust of the screw. In the present invention, the screw, itself, is used in such manner as to co-operate with the bit, so as to effect the desired angular thrust of the bit with respect to direction of thrust of the screw. The present invention uses this novel feature in combination with a holder constructed somewhat in accordance with the Lindmark Patent No. 1,443,752, which has been assigned to the assignee of this invention. However, it will be readily understood that the invention is not limited to its application to this specific tool holder, the inventive concept being broadly applicable to various other types of holders.

In the drawing, the numeral 10 indicates the shank, or body, of the tool holder, which may be straight, as indicated, or which may be angularly disposed or otherwise configured, in accordance with the particular operation for which the holder is designed. The forward end of the body is furrowed to form a lower bit receiving platform 11, and an upper overlying lip 12. The intermediate space, which is adapted to receive the shank 13 of the bit, is provided with a lower slanted surface 14, and preferably, with a contiguous upper slanting surface 15. The upper surface of the platform 11 is also preferably provided with an integral centrally disposed rib 16, which is adapted to co-operate with channels in the lower face of the bit, so as to assist in the retention of the bit against lateral displacement. As indicated in Figure 3, the channel 17 may be plural in number, so as to provide for a transverse adjustment of the bit in the holder. The body of the bit, which is provided with a cutting edge, is generally indicated by the number 18. The upper lip 12 is provided with a securing means, which is here illustrated as in the form of a set screw 19, the same being threadedly adjustable through the lip and having a conical point 20, so as to engage the bit.

While it has been customary, as in the patent referred to above, to secure the bit within the holder by the direct thrust thereon of the screw, some means are usually required to further assure the bit against outward movement. In the present invention, such assurance is provided by the engagement of the inner conical face of the screw with an oppositely inclined surface on the bit, thus, the thrust of the screw is both downwardly and rearwardly, so as to firmly press the bit back against the face of its receiving aperture.

As indicated in Figure 2, it will be noted that the thrust of the screw tends to move the bit rearwardly as well as downwardly, thus, creating a locking pressure between the screw and the slanting face 14. By this construction, it may be permissible to avoid the use of the customary front lip on the lower platform. Obviously, the axially extending rib 16 will engage the channels of the bit, so as to preclude lateral displacement.

As noted by the illustration of Figures 4 and 5, the provision of the co-operating slanting surface of the bit may be formed either by a transversely extending, substantially V-shaped slot 21, as in Figure 4; or by one or more conical depressions 22, as shown in Figure 5. In either instance, the conical taper 20 of the screw 19 will act to thrust the bit rearwardly as well as

downwardly, thus to lock it against the lower platform as well as against the surface 14. The structure here shown illustrates the possibility of wide ranges of tolerances in the formation of 5 the bit receiving aperture, thus, accurate and expensive milling operations in the formation of the holder may be avoided.

From the foregoing, it will be noted that the invention is simple in construction, provides ease 10 of placement and the removal of the bit from the holder, may be readily adjustable and is particularly designed to meet the rigid tests of accuracy which the metal working industries require. Obviously, the invention is not confined 15 to all of the details here illustrated or described. The size, shape and number of the ribs 16 or the channels 17 may be varied, as may be the number of screws 19, and the exact configuration 20 of both of the surfaces 14 and 15, and the configuration which provides the camming surface for the co-operation with the conical end 25 of the securing means. Therefore, numerous changes and modifications and the full use of equivalents may be made without departing from the spirit or scope of the invention as outlined in the appended claims.

What I claim is:

In a tool holder and tool bit assembly, a tool

holder comprising an elongated tool holder body of a substantially rectangular cross-section having, at one end thereof, a furcated formation characterized by a central transversely extending aperture, having an obliquely inclined end wall, 5 adapted to receive a tool bit shank; the lower furcation of the tool holder body forming, upon its upper surface, a bit-receiving platform having a plurality of independent ribs extending longitudinally of the tool holder body; the upper furcation having a lower surface parallel to the top surface of the lower furcation and extending longitudinally less than the lower furcation, and comprising a lip internally threaded to receive 10 therein, for threaded adjustment, a conical pointed bit securing screw in said lip and a tool bit mounted between said furcation, including a shank longitudinally recessed and receiving 15 therein, the longitudinal ribs of the upper surface of the lower furcation, and having this upper surface provided with means receiving the conical point of the securing screw of the upper furcation, said means having a cooperating side wall substantially parallel to said obliquely inclined 20 end wall and coacting with said screw to seat 25 said bit against said end wall of the furcation.

OLE SEVERSON.
